UNITED STATES PATENT OFFICE.

ALEXANDER H. DAVISON, OF ATHENS, GEORGIA.

DESIGN FOR A GLOVE-CASE.

SPECIFICATION forming part of Design No. 24,751, dated October 15, 1895.

Application filed August 14, 1895. Serial No. 659,286. Term of patent 14 years.

To all whom it may concern:

Be it known that I, ALEXANDER H. DAVISON, of Athens, in the county of Clarke and State of Georgia, have invented a new and original 5 Design for Glove-Cases, of which the following is a full, clear, and exact description.

Reference is to be had to the accompanying drawing, which is a front elevation of a glove-case embodying my design.

10 The features of the design comprise a body portion A of cylindrical appearance and having an ornamental crown B of serrated appearance at its upper end, and having, also, at its upper end a knob C of twisted or spiral 15 appearance. The body A is girted by concentric lines D, and its configuration is such that

it appears to have between the lines panels E, the same being arranged in pairs. A column F, having a spiral or twisted appearance, is seen above a base G, having a circular contour.

The leading feature of the design lies in the circular appearance of the body portion A and its panels E.

I claim—

25 The design for glove cases, substantially as herein shown and described.

ALEXANDER H. DAVISON.
